AUTOMATIC DRILLING AND COUNTER-
SINKING MACHINE

Leon T. White, Painesville, Ohio, assignor to
The Economy Engineering Company, Wil-
loughby, Ohio, a corporation of Ohio

Application October 3, 1936, Serial No. 103,895

17 Claims. (Cl. 77—23)

The invention forming the subject matter herein comprises an automatic drilling machine of the turret type, wherein all operations are carried on without interruption of the rotation of the turret. The machine herein shown and described as an illustrative embodiment of the invention is for the purpose of drilling and countersinking holes in bolts or rods, and some of the features of the invention are specifically adapted to this use. Others are of general application.

The invention also aims to provide a machine of the kind disclosed, and attachments, elements, and movements of the various sorts which are included, all adapted to permit operation on a variety of sizes and sorts of work, to permit all necessary adjustments, insofar as possible without stopping the machine, to reduce weight of moving parts, to maintain moving parts, so far as possible in motion without change of rate, and thereby avoid waste of power in overcoming inertia either of motion or of rest, to provide for the picking up of intermittently moving work, elements, or sub-organizations, and also for their stopping, with a minimum of jolting, roughness, or wear, and to get such parts from rest into motion at the speed of the part with which they temporarily move in the minimum distance possible and again to reduce them from motion at such speed to a condition of rest in the minimum distance possible consistent with smoothness of operation, to return such elements to their original positions without interference with parts which are in constant motion, to provide for the necessary passage of parts past one another with a minimum of unprofitable motion and with a minimum of interference with cycle of operations, so far as possible bringing such essentially unprofitable motions into a useful relationship.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In the accompanying drawings:

50 Fig. 1 is an assembly view of my machine generally on a central vertical plane, but with certain parts in elevation and certain parts on vertical sections out of the general plane;

55 Fig. 2 is a horizontal section substantially on

the plane 2—2, Fig. 1, but with certain elements in plan;

Fig. 3 is a horizontal section substantially on the plane 3—3, Fig. 1, but with certain elements in plan, chiefly showing the driving mechanism; 5

Fig. 4 is a horizontal section substantially on the plane 4—4, Fig. 1, showing in detail parts of the work feeding and gripping mechanism;

Fig. 5 is partly a plan view and partly a horizontal section, all taken on the broken plane 5—5, 10 Fig. 1, also showing parts of the work feeding and gripping mechanism;

Fig. 6 is a horizontal section through the turret on the plane 6—6, Fig. 1, showing spindle supporting and adjusting means; 15

Fig. 7 is a plan view on the plane 7—7, Fig. 1, showing in somewhat diagrammatic style the spindle driving means;

Fig. 8 is a development of the spindle-positioning cam; 20

Fig. 9 is a vertical section on the plane 9—9, Fig. 5 but with some elements in elevation;

Fig. 10 is an elevation taken substantially as indicated by the plane 10—10, Fig. 5, the direction of view being opposite to that of Fig. 1 and 25 of Fig. 9;

Fig. 11 is a detail of the countersink adjusting means, being a vertical section on the plane 11—11 of Fig. 9;

Fig. 12 is a plan view on the plane 12—12 of 30 Fig. 11, with parts in section;

Fig. 13 is an enlarged vertical section on the plane 13—13 of Fig. 4;

Fig. 14 is a vertical section on the plane 14—14 35 of Fig. 6;

Fig. 15 is an enlarged vertical section on the plane 15—15 of Fig. 8; and

Fig. 16 is a detail of the feed mechanism, partly in plan view and partly in oblique section, as indicated by the plane 16—16 of Fig. 10. 40

Before going to a detailed description, the organization and operation of the machine will be briefly outlined, reference being had particularly to Figs. 1, 5 and 10. A supply of work pieces, in this instance bolts B, is constantly fed down a chute C from a hopper, not shown. The hopper includes conventional arrangements for setting the work pieces all in one direction, in this instance placing all the bolts head up in the chute. A picker mechanism generally designated as P 50 takes the bolts from the end of the chute C and transfers them to jaws J which are part of the general turret organization. The turret mechanism including the jaws is in constantly rotation in the direction of the arrow I, and during 55

the movement of any bolt B from its initial position through a progress of about 300°, a hole is drilled transversely through the shank by a drill D, which then retracts itself, leaving the bolt still clamped in the jaw. Slightly beyond 300°, a countersink attachment K, best seen in Fig. 9, is attached to the turret organization for a short oscillation, during which the top and bottom of the bolt hole is countersunk by drills S. The countersinking completed, the jaw J opens at about 350°, dropping the bolt to a delivery chute, not shown, the countersink attachment K is released from its connection with the turret and returns to its starting point by the action of a spring G connected to K by a chain H. The base E of the entire machine includes a high side wall L which prevents splashing and waste of cooling and cutting liquids. The entire mechanism, in its preferred embodiments, includes two distinct drive systems, one powered by the motor M' in the base, which motor drives all of the mechanism hitherto described with the exception of the drills D, and a separate motor M² supported in an elevated position on a standard, and driving the drills D.

General organization

The base E includes a number of webs such as 11, 12, 13, 14 and 15 which support and house the principal drive system in the lower part of the organization, and which support a columnar structure rising from the base. The backbone of the columnar structure is a hollow stationary center column 20 upon which the entire turret system rotates. The center column is rigidly secured in the base E between a shoulder 21 and a spanner nut 22, thus clamping the shaft firmly in a hub 23 of the web 11, to which hub the column 20 is keyed at 24 against rotation. The hub 23 is further integrated to the base by other web elements such as are shown in horizontal section in Fig. 3. This shaft 20 rotatably supports the movable elements hereafter briefly described which collectively constitute the turret system. A lower inner sleeve 39 has bearings 31, 31 on the shaft and carries a worm gear 32 and an outer sleeve 33. The worm gear 32 is keyed to both sleeves as at 35 and held from below by a spanner nut 36 threaded to the bottom of 30. A gripping jaw system which is generally designated as 40, Fig. 1, and shown in detail in Figs. 4 and 9, is secured by bolts 41 between an outward flange 42 at the top of sleeve 30 and an outward flange 43 at the bottom of an upper sleeve 44. This sleeve 44 also includes an intermediate flange 45 and an upper flange 46. The sleeve 44 bears as at 47 and 48 upon the column 20. Immediately above the sleeve 44, and bolted to the flange 46, is the spindle housing 50. This housing bears upon the column 20 by the sleeve bearing 47 and the upper bearing 52. The connection to the upper bearing is by a sleeve 53 having a top flange 54 which is bolted to the housing 50 and forms part of the top of the housing.

Within the spindle housing 50 are a plurality of spindles which are described in detail hereafter under the caption "Drill system". The shaft of each spindle extends above the housing 50 and carries at its top a triple V-groove drive pulley 55 to which power is transmitted from the motor M² by a belting arrangement which is also described in the "Drill system" section of this specification. The top of the column 20 carries a stationary double bracket consisting of two half-

sleeves 56 and 57 clamped by bolts upon the column 20 above the spindle housing. The bracket 58 on one side holds the motor M², and is adjustable on a vertical hinge 58A by a threaded stud 58B for belt tightening, and the bracket 59 on the other side includes an additional extension arm 60 supporting an idler pulley 61 which can be set along a groove 145, also for belt tightening.

The jaw system J, best seen in Fig. 4, includes a cam ring 75 keyed as at 76 to the center column 20. The movable part of the jaw system, generally indicated at 40, Fig. 1, rotates about, and is actuated by this cam ring 75, as described in detail under the heading, "Jaw system".

The oscillating countersink attachment K, best seen in Figs. 1, 2 and 9, is movably supported upon the sleeves 30, 33 and 44 of the turret system by lower and upper bands 65 and 66 which are connected to brackets 67 and 68, integral with the housing of the attachment K. In detail, the lower band 65 is placed above the outer sleeve 33 and below a ring 70 bolted to the lower side of the flange 42. The upper band 66 is carried between the flanges 43 and 45 of sleeve 44. A protective skirt 71 extends out and down from the bottom of the band 65 and a housing 72 at the top of the same band protects the ring 70.

The entire moving assembly above described is supported by a flange 33A at the top of the outer sleeve 33 by a ball bearing 37 resting upon a hub 38 integral with the web 13 and connected to the hub 23 by an expanded housing wall 29 around the worm wheel 32, all integral with or rigidly secured to the supporting webs and base for the entire turret system.

Drive system

For the description of this system reference is made particularly to Figs. 1 and 3. The motor M', housed in the base E beneath the web 14, is suitably connected, as for example by a pinion 82, silent chain 81, and gear wheel 82, to the main drive shaft 83. This shaft transmits power by suitable gears to a worm 85, driving the turret system by the worm wheel 32; to flexible shafts 86 and 87 which drive the pick-up and countersinking mechanism respectively; and to a cam-shaft 88. The gear mechanism is carried and housed in parts of the base E generally defined by webs or walls such as 12, 14 and 15.

In general, the gearing is such as to drive the sleeves 30, 44 and spindle housing 50, that is the entire turret system, clockwise as indicated by the various arrows I in several figures. The worm 85, the flexible shaft 86, and the cam-shaft 88 take their power through a change speed gear box generally designated as 89 and which in itself is of conventional character. The flexible shaft 87 takes power from the main drive shaft 83 through a different gear train. Thus, the worm 85 and the shafts 86 and 88 are always driven at speed ratios which are constant among themselves, but which are controlled by the setting of the gear box 89. On the other hand, the countersink shaft 87 is driven at a speed which is not variable by the gear box 89, but is directly related to the motor speed.

To follow the two gear trains through their principal elements, the shaft 87 is driven from a miter gear 90 on main shaft 83 by a train of four pinions, the first of which bears reference character 91 and the last of which is fast to the shaft 87, all as illustrated in Fig. 3.

Power is transmitted from the pinion 95 on the main shaft 83 to gear 97 on the gear box countershaft, and from the gear 98 on the gear box variable speed shaft to a gear 99 on the shaft of the worm 85. A pinion 100 on the other end of the shaft of the worm 85 drives a gear 101 which actuates a horizontal shaft carrying a miter gear 102 driving the shaft 86. The pinion 100 also drives (through intermediate gearing) another spur gear 105 fast to the horizontal camshaft 88, Fig. 1. The shaft 86 also carries a spur gear 110 which, through an idler shown but not numbered in Fig. 3, drives spur gear 111 fast to the lower end of a vertical shaft 112, the upper end of which carries a cam 113, Figs. 1 and 2, partly controlling and causing the swing of the countersink attachment K, as described hereafter in the section "Feed and countersink system".

Returning to the horizontal camshaft 88, Fig. 1, this shaft carries rigidly a disc cam 120 and a cylinder cam 121. The disc cam actuates parts of the feed mechanism by means of a lever 122 as described in detail in the section "Feed and countersink system". The cylinder cam 121 operates a bell-crank lever 125 which in turn raises and lowers a lift rod 126, passing up through the interior of the column 20 and actuating a spindle-raising apparatus which is hereafter treated in detail in the section "Drill system".

Since the shaft 87 operates the mechanism of the countersink drills 5, Fig. 9, and nothing else, it will be apparent that a constant speed of these drills is maintained, irrespective of the speed of revolution of the turret system. A constant speed of the main drills D is also maintained irrespective of the speed of revolution of the turret by a belt drive from the motor M². It will be understood that the speeds of countersink drills and main drills can be controlled if necessary, as required by the character of the material operated upon, by governing the speeds of the motors M' and M². No arrangements for this are shown, since it can be accomplished by standard means.

The main drills D are driven by belts 141 from the separate motor M², Fig. 1, as described above at the end of the section "General organization".

Inasmuch as the entire spindle system is in constant rotation about the center column 20, it will be apparent from Fig. 7 that the pulley in the position 55A is out of contact with the belts 141 and that the pulleys 55B are not completely in contact with that belt. These are the pulleys on the three spindles which are out of operation because they have been lifted as at D', Fig. 1, to pass over the countersink attachment K. However, it would be disadvantageous to allow the drills on these pulleys to slow down, for the reason that there would be a waste of power in picking them up to speed again. In order to avoid such slowing down, the central belt 143 is provided which takes in the middle grooves of the pulleys 55, but does not engage the motor pulley 142. This belt 143 is related to the system of pulleys 55 in a sense just opposite to belts 141. Thus the belt 143, as best shown in Fig. 7, takes power from spindle pulleys in the positions 55C and 55D and transmits it to those in positions 55B and 55A. The belt 143 is kept tight by the idler 61, which can be clamped anywhere in the 70 radial slot 145.

Feed and countersink system

The feed and countersink system is mounted on and in the organization K, generally termed 75 the countersink attachment. This countersink

attachment, as previously mentioned, swings with the turret through an angular distance which in the present machine is about 30°, then is released and returns to the starting position, as will be explained in further detail below. During the forward swing (from full to dotted lines, Fig. 2) the ends of the hole which has been drilled in the bolt are countersunk, the bolt is discharged from the gripping jaws J, and simultaneously a new bolt is taken from the chute C 10 by the picker attachment P and so positioned as to be gripped by that pair of jaws J which was unloaded on the previous swing. All this accomplished, the countersink attachment is released from its connection with the turret and 15 swings back quickly to its starting point.

Relating the foregoing general description to Fig. 4, the countersink attachment K is here shown in the starting position of its swing, corresponding to the solid position of Fig. 2. The 20 hole in the bolt B10 is beginning to be countersunk by the drills S, Fig. 9, while the pair of jaws next in advance, which pair dropped a countersunk bolt an instant previously when K was in the dotted line position, K', Fig. 2, is 25 about to close upon a new bolt B'.

The bolts B, as mentioned, are placed by conventional hopper mechanism not shown head up in the slot of the feed chute C, as shown in Figs. 2 and 10. At the bottom of the chute C 30 there is a cross slide 201 reciprocated in appropriate guides by means of the upper end 122A of a bellcrank lever 122 pivoted at 122B in depending arms 122C, supported from a plate 122D carried on the base web 14. The lower end 122 35 carries a roller, shown in Fig. 1, as riding on cam 120. A linkage 202, Fig. 2, connects 122A to the slide 201. The cross slide 201 has on its forward end extension fingers 205 and 206 notched to take the lowermost of the bolts B from the 40 chute, when the slide 201 is in its retracted position, bringing the aligned notches 207, 208 into registry with the end of the chute. The fingers 205 and 206 are carried removably and adjustably in a slot 210 in the forward end of the 45 slide, and can thus be varied for different sorts of work. By reference to Fig. 10 it will be seen that the fingers 205, 206 operate in a plane inclined somewhat forward from the vertical, so that gravity holds the bolt B in the notches 207, 50 208, and the head of the bolt prevents it from sliding down and out. During the outward travel of the slide 201, a picker finger 215, Figs. 10 and 16, which is part of the mechanism P carried on the forward side of the housing of K, takes hold 55 of the bolt B, and the mechanism P then moves from the dotted to the solid line position of Fig. 10 and there inserts the bolt in one of the jaws J.

As previously mentioned, the picker mechanism P is attached to the side of the countersink mechanism K, and it is so timed as to move from the dotted to the solid line position of Fig. 10 during the movement of the countersink mechanism from the solid position K to the dotted line position K' of Fig. 2. The outward movement of the 60 slide 201 synchronizes with the swing of the countersink attachment K and with the initial attachment of the picker finger 215 to the bolt B. Reference to Fig. 2 shows that the travel of K is much greater than that of the slide 201. Thus, 65 shortly after the picker finger grips the bolt, the bolt is carried clear of the guide fingers 205, 206, and the slide 201 is retracted by the operation of cam 120. The flexible mounting of the picker finger permits the bolt to clear the shallow notch- 70 75

es 207, 208, as will be apparent from the description of the finger.

Referring to Figs. 10 and 16, the preferred form of picker finger mechanism generally designated as 215 comprises a gooseneck arm 209 keyed on a rod 221, and having a bolt 209A threaded therein. Above the arm 209 there is pivoted on the rod a middle bar 211 with an offset integral rear extension 211A. The bolt 209A passes through a larger transverse bore in 211A and carries an outside compression spring 209B normally holding the parts in the relative positions of Fig. 16, but obviously allowing counterclockwise yield. Side bars 212 are yieldably held against the sides of 211 by compression springs such as 212A on bolts 212B. The ends of the bars 211 and 212 are notched, as shown, for better engagement with the bolt B. Suitable adjusting means, not shown, permit the picker finger mechanism to be placed where desired upon the rod 221 according to the length of bolts or other work to be fed. It is apparent that more than one mechanism 215 may be used upon the rod 221 when work of exceptional length is in hand.

The finger 215 addresses the bolt from slightly above the dotted line position of Fig. 10, and while the slide 201 is retracted. After engagement, the rod 221 (controlled by cam 320, Fig. 5) makes a slight reverse movement, clearing the bolt from the notches 207, 208 while the slide 201 and the attachment K are both advancing, then, after the bolt is cleared, the rod 221 is swung upward by rotation of a horizontal shaft 230, bearing in the boss 230A (Fig. 4), to the outer end of which shaft there is fast an arm 231 wherein the upper end of the rod 221 is adjustably secured. The mechanism whereby the shaft 230 is oscillated will be described in connection with the other operating mechanism of the countersink attachment K, to which it is closely related. When the rod 221 swings to its upper solid line horizontal position, Fig. 10, the bolt is parallel thereto, and is then pushed forward by a rod 240 axially moved by a crank 241 yoked thereto. The crank 241 is pivoted to a boss 242 which is also fixed to the oscillating shaft 230. As shown in Fig. 4, a cam 245 keyed to shaft 86 and actuating a bellcrank lever 246 and a plunger mechanism 247 causes movement of the lever 241, as explained in some detail hereafter, thus pushing the bolt B, still horizontal, at the appropriate time, to a forward position in which its front end is engaged by the jaw mechanism J. Gauge blocks 250 adjustable in a horizontal slide 251 on the side of the attachment K limit the upward travel of the bolt B by engagement with the side of the bolt and the outer of these blocks limits its horizontal travel by engagement with the under surface of the bolt head, all as shown in Fig. 10. For different thicknesses of bolts different gauge blocks may be substituted. For different lengths of bolts, the rod 240 may be set appropriately by the nut 255.

In detail, Figs. 4 and 13, the plunger mechanism 247 includes a sleeve 247A axially movable within the hollow shaft 230, and thus moving the bellcrank 241. A central plunger 247B, surrounded by compression spring 247C, builds up a pressure to overcome the resistance of spring 230B and cause snap action of the push rod 240 when the bellcrank lever 246 is moved out by the cam 245. The lever 241 and rod 240 rotate with the shaft 230.

The picker finger system is given its vertical swing by a cam 320 carried in a top housing 321 on the main housing K. This cam, seen in Figs.

5 and 9, is ridden by a roller 325 carried by one side of a partly toothed quadrant 330 keyed to a vertical shaft 327. An arm 331, keyed higher on the same shaft, is biased clockwise by the pull of a tension spring 340, the outer end of which is fast to an arm 341 rigidly secured to the top of housing K. The toothed segment of 330 engages a pinion 335 on the upper end of a vertical shaft 336 whose lower end carries a bevel gear 337 meshing with a bevel gear 338 on the inner end 10 of the horizontal shaft 230. It will be remembered that this horizontal shaft 230, best seen in Fig. 4, carries all the elements of the picker and feed mechanism.

Obviously, rotation of the cam 320 results in 15 oscillation of the picker mechanism P, and the rotation of cam 245 on the same shaft relates the action of the push rod 240 to the other elements of the feed cycle. The high side of the cam 320 positively retracts the picker mechanism and 20 tensions the spring 340, while the low side releases the spring, resulting in the bolt feed by spring drive, with incidental safety which would not be had if the feed were positive. The cam 320 is appropriately notched at 321' to cause the 25 slight rearward movement of arm 331, whereby the bolt B is lifted from the notches 207, 208. As previously pointed out, the axle motion of the rod 240 also includes transmission of power by loading the spring 247B; thus the entire feed system is 30 spring protected and neither the jaws nor any other part of the mechanism can be injured by a feeding jam.

Although the countersinking operation completes the cycle which is begun by the feed mechanism just described, the arrangement of the machine makes it convenient to describe completely the entire countersinking apparatus at this point. The housing K, which is preferably a casting of light weight such as aluminum or even lighter 40 materials, includes the integral arms 67 and 68 and is rotatably carried upon the turret system at 65 and 66, as has already been described.

Within the housing, besides the principal operating elements for the picker P, just described, 45 there are also the drive and control elements for the countersinking drills S, and the devices for attaching K to the rotating turret and detaching it therefrom.

In order to cause movement of K from the 50 solid line position to the dotted line position K' of Fig. 2, which movement will hereafter be termed the operating swing, a lock pin 300 successively engages notches 301 of the ring 70 in the constantly-rotating turret system, all as 55 shown in Fig. 2. The return swing is by the spring G, connected to K by the chain H, and tensioned by the operating swing.

The timing and drive of the lock pin 300 is by a cam 302 on shaft 86 working a bellcrank 60 lever 303 yoked to a collar 304 at the rear end of the latch rod 305. Retraction of the latch compresses a return spring 306. Nuts 307 accessible through a plugged hole 308 permit adjustment of the latch for length.

The operating swing of the entire attachment K is given an initial impetus by a cam and lever mechanism, Fig. 2, so as to avoid a jerky start and too great a strain on the lock pin. The same mechanism also cushions the stop of the 70 return swing. This mechanism comprises a bellcrank arm 360 intermediately pivoted to the base E, linked at its longer end at 361 to the housing of K, and carrying a roller 362 at its short end. This roller 362 rides on the cam 113, also 75

Drill system

seen in Fig. 1, appropriately shaped. The entire countersink attachment K is thus started clockwise at a rapidly increasing rate of motion which, however, at its maximum is slightly less than the turret speed, in order that the notch 301 may quickly catch up to the lock pin 300, whereafter the rest of the operating swing is of course synchronous with the turret movement. Similarly, the return swing, under the tension of spring G, is terminated without shock by the roller 362 on the cam 113.

The countersink drills S, as shown in Fig. 9, are fed axially by identical upper and lower arms 400, centrally pivoted, and tilted by cams 401 fast to the shaft 86. The cams 401 may be altered in axial position upon the shaft 86 by means of an adjusting mechanism shown in preferred form in Fig. 11, one end of which, 402, is visible in Fig. 9. This adjustment is for depth of countersink cut, and is accomplished in the present example by making the upper portion of the shaft 86 tubular (Fig. 11) and priming each of the cams 401 as at 405 through a paraxial slot such as 406 to a sliding block as 407, threaded to a central rod 408, suitably threaded right and left. The rod 408 is also threaded at its upper end through a plug 409 in the top of the tubular shaft 86.

Each drill is rotated from the shaft 87 by gear trains which are shown in Figs. 2 and 5, and partly in Fig. 9. The lower gear train comprises a spur gear 405 rotating with the shaft 87 and directly driving a pinion 406 on the chuck of the lower drill S. This spur gear 405 drives the upper countersink drill S by a train comprising idler 410 (Fig. 2), pinion 411 keyed to the lower end of vertical shaft 412, the upper end of which has keyed thereto a gear 413 (Fig. 5), in turn driving idlers 414, 415 and 416, the last of which 40 engages with the pinion 417 on the chuck of the upper countersink drill S.

Jaw system

The jaw mechanism for holding the bolts B during drilling is shown in detail in Fig. 4, and is also partly visible in Figs. 1, 5, 9 and 10, being generally represented by reference character J.

The jaws in the machine illustrated are ten in number, all constantly rotating as part of the general turret system. Each jaw comprises a stationary element 501 solidly fixed between the flanges 43 and 42 (Fig. 9), and including a gripping face 502 which is notched horizontally as at 503 to take the side of a bolt and notched vertically as at 504, above and below to allow passage of a drill D or S. The movable member of each jaw comprises a bellcrank lever 510 carrying an adjustable gripping stud 511 at its outer end by which the end of a bolt B is held in the notch 503. The lever 510 is constantly urged in the closing direction by a compression spring 512 housed in a socket 513 in the stationary element 501. The inner end of the arm 510 carries a roller 515 which is out of contact with anything during the greater part of the turret revolution, but which rides over a nose 520 of stationary ring cam 75 to open the jaw to drop the completed work and to receive a new work piece.

The jaw at the extreme left of Fig. 4 is shown open, with a new bolt B' just being inserted therein. Before the picker finger 215 has let go of the bolt, the roller 515 will have ridden off the cam nose 520, and the movable arm 510 will thus have gripped the bolt.

The drill system is shown in Figs. 1, 6, 7 and 8 and in the machine illustrated comprises ten identical drills circumferentially disposed at equal distances in the housing 50, 54. These drills D are kept in constant rotation by the arrangement shown in Figs. 1 and 7, already described under the caption "Drive system". Each drill consists of a spindle 601 having a chuck 602 at its lower end holding a bit 603. At the upper end a shaft 604 has a spline connection to the pulley 55. The drill D generally is supported from and aligned by ball bearings 606 and 607 on its upper end. The spindle 601 is supported in a sleeve 610, the upper part of the sleeve being threaded as at 611. By means of collars 612 and 613 at the top and bottom respectively of the sleeve 610, the axial movement of the sleeve is imparted to the spindle, rotation being constantly maintained by the spline arrangement 604. Thus, the bits 603 are moved up and down by the sleeve.

The sleeve 610 has three distinct possible sorts of vertical movement, the first being an adjustment by the sleeve threaded portion 611 to govern the range of operation of the bit 603 according to thickness of the work and other factors; the second being by cam track 652 for feed and "spotting", and the third being an extensive quick lift and drop to pass the bit over the arm 30 68 and return it to the work.

For all three movements each sleeve 611 is supported in a carrying block 615 vertically slidable with a close fit on two guide posts 616 and 617.

For adjustment, as shown by Fig. 14 and by 35 one of the blocks which is sectioned in Fig. 6, a worm wheel 620 is rotatably mounted but axially immovable in the carrying block 615, this wheel being internally threaded upon the threads 611. A worm 621 horizontally disposed in the 40 guide block actuates the worm wheel, this shaft having a square head 622 to which a wrench can be applied through an opening 623 in the housing 50. A keyway 611A through the sleeve threads 45 611, and keys 611B, prevent the sleeve 610 from turning.

Each block 615 also carries an inwardly-directed horizontal roller 650 travelling in the cam track 652 whereby the second and third movements above-mentioned are imparted to the drills, as 50 described under the next caption, "Cam and lift".

Cam and lift

See Figs. 1, 6, 8 and 15.

The working motion of the drills D, that is, the 55 second and third motions mentioned in the foregoing section, are imparted by a cam track 652 which encircles the central pillar 20 and which does not rotate. The rollers 650 travel in this track, only one being visible in Fig. 6 because the 60 others are below the top track rail 651 in that figure.

In detail, a heavy hollow core 670, outwardly flanged at the top, is keyed at 671 to the central pillar 20, fitting thereon from just above the bottom of the turret housing 50 to just below the sleeve 53. An adjustable cam shell 669, top flanged at 684, and rendered flexible by vertical slots from the bottom of flange 684 to the top of the upper cam track 651 at intervals as indicated at 672, encircles 288° of the core in the embodiment here illustrated. The upper and lower cam rails 651, 653 are secured to the shell 669, as seen in Figs. 8 and 15. These rails define the track 652 which has a general downward 75

inclination throughout to extent except for certain changes of direction hereafter explained. It is by this inclination that the drills D are fed to the work.

5 Reference to Fig. 8 shows that this general inclination is with reference to the horizontal plane of the upper and lower edges of the shell 669. In order to vary the total amount of feed, provision is made to change the form of the shell 669 from cylindrical to spiral by a jack screw 680 (Fig. 1) threaded through the core flange and rotatably headed into the shell flange 684 at 681 near the free end.

The shell 669 is anchored to the core by a bolt 15 at 675, which immovably fixes the lower end of the track 652, with the result that adjustment of feed for thicker work is by increasing the lift of the drills. Each segment of 669 has two bolt holes, 676, each of which varies progressively from 20 the next in length and inclination appropriately for the allowable movement. A gage 677 near the jack screw head measures the track setting.

Just beyond the anchored end of the cam track there is a lift slide 700, occupying 27° of the circumference in the particular machine illustrated, guided vertically in the core 670 and conforming to the outer surface of the core, all as best seen in Figs. 6 and 8. A stud 701 passing through slots in the column 20 and core 670 provides for 30 raising and lowering of the slide 700 by the rod 126 which is actuated by the cam 121. Rails horizontally secured to the bottom of the lift slide define the track 652A thereon.

At its bottom position this track registers as 35 shown with the low end of track 652. While slide 700 lifts the roller 650 is continuing its clockwise travel, the timing being such as to define approximately the broken line path II, Fig. 8, so that at the top of the lift the roller moves onto the stationary horizontal track section 652B. The rails defining this section are secured to an immovable segment 710 which is 45° long and riveted to the core 670.

Beyond 652B the track, now on the free or movable end of shell 669, slopes sharply downward as designated by 652C. At the upper end of section 45 652C the rails 651 and 653 are relieved as shown to allow passage of rollers 650 at all settings of the track. At the bottom of 652C a section 652D follows a short irregular path comprising successively a run gently downward at the general feeding inclination, a quick rise, a momentary flat, and a sharp drop. Thereafter the general feed inclination of 652 begins.

55 The purpose of the lift slide 700 is to remove the drill from the finished work, B10 of Fig. 4, to a height to clear the arm 68. The track section 652B holds the drill up crossing the arm, the section 652C lowers it for "spotting", while the 60 section 652D governs spotting, temporary clearing, and return to work.

Spotting

See Figs. 5, 8 and 10.

65 To bring the drill bit 603 to accurate working position a spotting bushing 800 is carried through an ear 801 extending from a skirt 802 on the band 66 of the countersink attachment K. Circumferential grooving 803, diametrically disposed on 70 each side of the bushing 800, minimizes the necessary clearance lift of the drill bit 603, increasing the speed of spotting.

It will be recalled that from about 315°, Fig. 8, to 69½° the attachment K is locked to the 75 rotating turret system. It will also be seen, Fig.

5, that the spotting bushing 800 is well in advance of arm 68. Thus during the feeding of the new bolt to the jaws J the bit 603 can move down into the bushing, guided by track section 652C. From the station at 40½° to 54½° the bit, guided near its point by the bushing drills into the work sufficiently to start the hole. It then quickly lifts to clear the bushing ear 801 for the return swing of attachment K, and immediately drops back into the hole in the bolt.

10 5 10

Operation

The operation has been described generally after the brief description of figures of the drawings, and in detail concurrently with descriptions 15 of the mechanism.

It will be understood that all exact positions, proportions, details and the like shown herein are those of a specific illustrative embodiment of the invention, and are not to be construed as 20 limitations upon the invention or upon the range of equivalents in the interpretation of claims.

What I claim is:

1. An automatic machine comprising in combination, a turret system, a plurality of work stations included therein, means for maintaining said turret system in rotation constantly as to direction and speed, an attachment adapted to join for a limited arc in the movement of one station of said turret system and to return to its 30 starting point for similar participation in the movement of the next successive station, said turret system comprising means for performing the principal operation upon the work, and for discharging the completed work, said attachment comprising means for feeding work to the 35 turret system including positioning it therein.

2. An automatic drilling machine comprising, in combination, a standard, a turret rotatable thereon, said turret comprising a plurality of 40 work stations, gripping jaws at each station and a main drill thereabove; an attachment adapted to oscillate upon said standard coaxially with said turret, said attachment overlapping the plane of the jaws, feeding means carried by said attachment and adapted to supply work to said jaws, countersinking drills carried by said attachment; means for axially positioning the main drills, said means including a cam track upon the standard, vertical lifting means for a portion of 45 said cam track adapted to raise the drills to clear said attachment, said cam track including means to return the drills to work-engaging level quickly and to progress the drills through the work; means carried by said column and operatively 50 coordinated to the cam track for opening and closing said jaws to discharge completed work and receive new work.

3. An automatic drilling machine comprising in combination a rotatable turret system with 60 work stations therein, each of said work stations including a drill, means for moving each of said drills paraxially with respect to the turret axis, an attachment mounted concentrically with the 65 turret and oscillable alternately with and against the turret movement, said attachment including an arm which lies in the working zone of the drills, means for removing said drills from the path of said arm, work-holding jaws immediately below said drills and constituting part of the 70 turret system, a spotting guide carried by said attachment arm immediately above the path of said work-holding jaws, and means for moving said drills successively to apply each drill bit to the work through said spotting guide and to feed 75

said bit a short distance into new work under said guide, and thereafter to momentarily raise said bit to clear said spotting guide for the return swing of said attachment and next to return the bit to the work in the spotted hole.

4. An automatic drilling machine comprising in combination a rotatable turret system with work stations therein, each of said work stations including a drill, means for moving each of said drills paraxially with respect to the turret axis, an attachment mounted concentrically with the turret and oscillable alternately with and against the turret movement, said attachment including an arm which lies in the working zone of the drills, means for removing said drills from the path of said arm, work-holding jaws immediately below said drills and constituting part of the turret system, a spotting guide carried by said attachment arm immediately above the path of said work-holding jaws, and means for moving said drills, said drill-moving means including a cam track for quickly lowering the bit through the spotting guide and into the work after clearance of the auxiliary attachment arm, followed by momentary lift for clearing the drill from the spotting attachment, followed by return to the main working position and feeding track.

5. In an automatic machine for operating upon work pieces, said machine comprising a turret adapted for constant rotation and an auxiliary attachment adapted for oscillation alternately with and against turret movement, the combination of mechanism for locking said attachment to said turret for the "with" motion only, said locking attachment comprising a bolt adapted to lock into successive positions on said turret, said positions being coordinated with the work stations, spring means for holding said bolt in locking engagement and positive means for releasing said bolt, the "with" swing of said attachment being actuated by the turret drive, supplemented by a cam, and the return swing of said attachment being actuated by spring and braked by the same cam.

45. 6. In an automatic machine, in combination, a turret comprising a plurality of constantly spaced work stations, means for imparting constant orbital travel to said turret, each work station including a work holding means and a work-50 ing tool, and work-feeding means, said work-feeding means comprising a plurality of work-transfer elements at successive distances from the turret, means for moving all of said transfer elements in the general direction of turret travel 55 during a feeding cycle, but for different distances, the travel of the inner elements continuing through a limited arc after that of the outer is ended and during such continuance being equal in angular speed to that of the turret, and means 60 for transferring work from the inner transfer element to the work holding means at a station during the period of equal angular speed.

7. Feeding mechanism adapted to move work pieces from an external supply source to a constantly moving working apparatus, which apparatus includes a plurality of stations, means connecting said feeding mechanism to said work apparatus to be carried therewith adjacent to each station successively for temporary participation in the movement thereof, means operable during such participation to engage a work piece at said external supply source and transfer the same first to approximate working position and then to accurate working position and finally to release said

work piece, followed by disengagement of said locking means.

8. An automatic drilling machine comprising in combination a constantly rotating turret, drilling mechanism carried thereby, clamps carried thereby adjacent said drilling mechanism, and a work-feeding mechanism, said work-feeding mechanism comprising a picker movable from a supply of elongated work-pieces externally placed with respect to the turret to a horizontal position 10 radial to the turret and adjacent said clamps, means moving said picker, and means associated with said picker for further moving each work-pieces radially into said clamp, and means moving said picker and its associated means with the 15 turret.

9. In a machine of the class described, a feeding attachment comprising in combination, a horizontal shaft, an arm fixed thereon, a rod in the plane of said arm and at a right angle thereto, and a picker finger on the end of said rod opposite said arm, also at a right angle and directed on the same side of the rod as the arm, a push bar intersecting the axis of said shaft parallel to said rod, and means for axially reciprocating said push bar at the end of the up-swing of said rod against a work-piece held in said picker finger.

10. In a machine having a constantly-rotating turret during the rotation of which an operation 30 is performed upon a work piece, work piece clamps carried by said turret, work feeding means comprising a chute presenting work pieces singly, a slide movable in a direction tangent to the turret rotation and including a work piece holder 35 alternately registerable with said chute and with said slide, a picker mechanism oscillable between the work piece holder of said slide and a position in alignment with the turret clamps, locking means between said work feeding means and said 40 turret operable after the work piece has been picked from the slide, and releasable after the work piece has been clamped in the turret jaws.

11. In a mechanism of the class described, a constantly rotating turret, an attachment concentrically oscillable therewith, a lock between said attachment and said turret, a spring for locking said lock and positive actuating means for unlocking said lock, a feed mechanism carried by said attachment, positive retracting 45 means for said feed mechanism and spring drive means for the feeding stroke, said spring drive means comprising a spring loaded by the retracting stroke of said mechanism.

12. An automatic drilling machine comprising, 55 in combination, a constantly rotating turret, drilling mechanism carried thereby, work-holding means operatively adjacent said drilling mechanism, a work-feeding mechanism in combination therewith, means in said work-feeding 60 mechanism constraining it to travel in fixed position with the turret through an arc of the travel of the latter, and means in said work-feeding mechanism cooperable with said work-holding means to complete the transfer of work to said 65 holding means during the maintenance of the fixed position.

13. In a turret machine comprising a plurality of work stations each having a work-piece clamp and a principal working tool, and an attachment connection at each station, an attachment comprising in combination a bracket pivoted concentrically with the turret, a lock engageable with said connection, work-finishing tools, means for applying and removing said tools to and from the 75

- work, and lock fastening and releasing means, and synchronized actuating elements for said fastening and releasing means and for said applying and removing means, to apply the tools after locking and to remove the tools after un-locking, and a feed mechanism movable with said attachment comprising a rod, a work piece carrier on said rod and a drive swinging said rod back and forth through an arc in a plane trans-
5 verse to the movement of the attachment, said work-piece clamps being successively adjacent said carrier at the inner end of said arc, a work-piece source adjacent said carrier at the outer end of said arc, and synchronous connections be-
10 tween said feed mechanism and said lock fastening and releasing means, whereby said bar swings from outer to inner end of said arc while said lock is fastened.
14. In an automatic machine, in combination, a turret, rotating mechanism therefor, and a plurality of drills carried thereby, a drive for said drills, an attachment oscillable alternately with and against said turret, and including a mechanism for locking and unlocking said attachment to and from the turret, and a work feed mechanism, and work finishing tools, and mechanism for moving said finishing tools into and out of engagement with work, a second and independent drive means, a constant speed connection from said second drive to said work finishing mechanism, a variable speed connection from said second drive to said turret rotating mechanism, and to said locking and unlocking mechanism, and to said feed mechanism and to said finishing mechanism, whereby said mechanisms other than the drills and the finishing mechanism may be maintained at constant speed relationship among themselves but varied as a whole with respect to the drills and finishing tools.
15. In an automatic machine for operating upon work pieces, said machine comprising a turret adapted for constant rotation and an auxiliary attachment adapted for oscillation alternately with and against turret movement, the combination of a supply source for work-pieces outside said turret and work-holding jaws included in said turret, a feeding mechanism car-

ried by said auxiliary attachment, said feeding mechanism comprising an arm adapted to swing out to said supply source and in to said work-holding jaw, a positive drive for said arm for the outward swing, and spring means, loaded during the outward swing, for energizing the return swing. 5

16. Work-feeding apparatus for a machine of constantly travelling stations, said feeding apparatus comprising, in combination, a chute adapted to present work pieces sequentially and in predetermined position, a picker finger adapted to be carried horizontally and to swing vertically, means for carrying said finger in travel with a travelling station, a slide substantially tangential to the arcuate path imparted to said picker finger by said travelling station, means for reciprocating said slide, means for swinging said picker finger in an arc transverse to station movement from a supply position adjacent said slide to a delivery position adjacent a work station, means synchronous with said swinging means for moving said first-named means and said picker finger with part of the travel of a station, a work piece holder upon said slide and registering at one end of slide travel with said chute and registering at the other end of slide travel with the supply position of the picker finger. 10

17. In a turret machine comprising a plurality of work stations each having a work-piece clamp and a principal working tool, and an attachment connection at each station, an attachment comprising in combination a bracket pivoted concentrically with the turret, a lock engagable with said connection, work-finishing tools carried by said bracket, means for applying and removing said tools to and from the work, and lock fastening and releasing means, a yieldable drive connection to said fastening means and a positive drive connection to said releasing means, said positive and yieldable drives being synchronized with the said means for applying and removing said tools, to apply the tools after locking and to remove the tools before unlocking. 35

LEON T. WHITE.

CERTIFICATE OF CORRECTION.

Patent No. 2,165,774.

July 11, 1939.

LEON T. WHITE.

It is hereby certified that error appears in the printed specification of the above numbered patent requiring correction as follows: Page 7, second column, line 13, claim 8, for the word "each" read such; and that the said Letters Patent should be read with this correction therein that the same may conform to the record of the case in the Patent Office.

Signed and sealed this 15th day of August, A. D. 1939.

Leslie Frazer

(Seal)

Acting Commissioner of Patents.
